CLAIM

The ornamental design for a monitor, as shown and described.

DESCRIPTION

FIG. 1 is a top, front, right-side, perspective view of a monitor showing our new design;

FIG. 2 is a bottom, rear, left-side, perspective view of the monitor shown in FIG. 1;

FIG. 3 is a front elevational view of the monitor shown in FIG. 1;

FIG. 4 is a rear elevational view of the monitor shown in FIG. 1;

FIG. 5 is a left-side elevational view of the monitor shown in FIG. 1;

FIG. 6 is a right-side elevational view of the monitor shown in FIG. 1;

FIG. 7 is a top plan view of the monitor shown in FIG. 1; and,

FIG. 8 is a bottom plan view of the monitor shown in FIG. 1.

The broken lines shown in the drawings represent portions of the monitor that form no part of the claimed design.

1 Claim, 7 Drawing Sheets
